DISPLAY STAND FOR TROUSERS OR THE LIKE

Maxwell Revenson, Massapequa, N.Y., assignor to Neal Goldman Associates, Inc., New York, N.Y., a corporation of New York

Application May 27, 1959, Serial No. 56,097

Term of patent 7 years

(Cl. D80—9)

Fig. 1

Figure 1 is a view in perspective of a display stand for trousers or the like embodying my new design;

The dominant features of my design reside in the portions shown in full lines.

I claim:

The ornamental design for a display stand for trousers or the like, substantially as shown and described.
